UNITED STATES PATENT OFFICE.

CECILIA K. SCHMIDT, OF BOSTON, MASSACHUSETTS.

BANK-CHECK, &c.

1,227,004.

Specification of Letters Patent.

Patented May 22, 1917.

Application filed June 30, 1916. Serial No. 106,914.

To all whom it may concern:

Be it known that I, CECILIA K. SCHMIDT, a citizen of the United States, residing at Boston, in the county of Suffolk and State of Massachusetts, have invented new and useful Improvements in Bank-Checks, &c., of which the following is a specification.

This invention relates to a money order, such as a bank check, adapted to be treated by cutting away portions of its body to leave value-indicating numerals exposed in close proximity to the cut edges, and arranged to collectively indicate the amount for which the check is drawn, the treated check being unalterable to raise its value.

The object of the invention is to provide a check of this character adapted to be drawn to represent large or small amounts exactly and treated to prevent raising, without requiring any enlargement of the check from the ordinary standard dimensions and without encroaching objectionably on the space devoted to the usual indicia printed and written on the check.

The invention is embodied in the improvements which I will now proceed to describe and claim.

Of the accompanying drawings forming a part of this specification:

Fig. 1 represents a face view of a check embodying the invention, before the treatment which prevents the raising of its value;

Fig. 2 represents a view similar to a portion of Fig. 1, showing the check after said treatment;

Fig. 3 represents a view of the back of the portion of the check shown by Fig. 2.

The same reference characters indicate the same or similar parts in all the views.

A bank check α embodying my invention may be of the usual oblong form and may have the usual dimensions. In carrying out my invention I print upon the left-hand end portion of the body of the check two columns of value-designating characters, preferably numerals, said columns extending longitudinally of the check or substantially in the direction of its upper and lower longitudinal edges and being spaced apart so

that one column is adjacent to the upper edge and the other to the lower edge of the check, and room is afforded between the columns for written and printed indicia on both the front and back of the check.

As here shown the column adjacent to the

lower edge of the check is composed of three rows b , c , d , arranged in stepped formation, one end of the row b overlapping the adjacent end of the row c , and the opposite end of the row c overlapping the adjacent end of the row d . The value of the characters progressively decreases from the left to the right hand end of each row, and the check bears indicia indicating that said characters represent dollars.

The column adjacent to the upper edge of the check, as here shown, is composed of three rows b' , c' , d' , arranged in stepped formation like the rows b , c , d . The characters of the row b' represent dollars, and those of the rows c' , d' , represent cents.

In this example of the invention, the check is drawn for fifty-six hundred and sixty-seven dollars and fifty-nine cents.

After writing the check it is cut away, as indicated by Fig. 2, to form steps on its longitudinal edges, six steps being formed in the example here given. In the lower column one step exposes "5000", the next "600", and the third "60". In the upper column one step exposes "7.00", the next ".50", and the third ".09".

The check thus treated cannot be successfully raised, because any value-raising change in the indicia written on the body of the check can only be correspondingly made on its stepped edges by adding sections of paper bearing numerals which were previously cut away, a feat which cannot be accomplished without detection.

As will be seen by Figs. 2 and 3, the described treatment does not leave the check with a narrow attenuated end portion liable to be accidentally torn away, the treated or stepped end portion of the check being so proportioned that its strength and durability are not materially impaired, and space is left on the back of the check for endorsement between the stepped edges, as shown by Fig. 3.

The stepped formation of the columns and the characters forming the same in this embodiment of the invention enable the check to be prepared to represent an amount exceeding ten thousand dollars, without requiring any increase in the size of the check.

Having described my invention, I claim:

1. A money order, such as a bank check, having rows of value-designating characters forming stepped columns, said columns be-

ing arranged adjacent to the upper and lower edges of the left-hand portion of the check, said columns being spaced apart to afford room between them for indicia of the 5 check, the values of said characters in each row decreasing progressively from left to right, and the values in each row being unlike those in the other rows, the arrangement of said rows being such that the check may 10 be cut to remove characters from said columns so that thereafter the characters at the left ends of the rows collectively indicate the amount for which the check is drawn.

2. A money order, such as a bank check, 15 of oblong form, having a plurality of longitudinally extending rows forming stepped columns of value-designating characters, said columns being arranged respectively ad-

jacent to the upper and lower edges of the left-hand portion of the check and being 20 spaced apart to afford room between them for indicia of the check, the value-designating characters of each row indicating values unlike those in the other rows, and the values of said characters in each row decreasing 25 progressively from left to right, the arrangement of said rows being such that the check may be cut to remove characters from the left-hand ends of said rows so that the characters at the extreme left of the rows thereafter 30 collectively indicate the amount for which the check is drawn.

In testimony whereof I have affixed my signature.

CECILIA K. SCHMIDT.
